FOREIGN PATENT DOCUMENTS

EP 3184183 A1 * 6/2017 ..... B21D 39/20

Primary Examiner — Patricia A Palasik*(74) Attorney, Agent, or Firm* — Wang Law Firm, Inc.(57) **CLAIM**

The ornamental design for a tube straightening device, as shown and described.

DESCRIPTION

FIG. 1 is a front top perspective view of a tube straightening device in accordance with the present invention;

FIG. 2 is a rear bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines in the drawings depict portions of the tube straightening device which form no part of the claimed design.
